UNITED STATES PATENT OFFICE.

WILLIAM A. BRANDT, OF NEW YORK, N. Y.

SASH-PULLEY.

1,188,889.

Specification of Letters Patent. Patented June 27, 1916.

Application filed February 9, 1916. Serial No. 77,185.

To all whom it may concern:

Be it known that I, WILLIAM A. BRANDT, a citizen of the United States, and a resident of the city of New York, borough of Manhattan, in the county and State of New York, have invented a new and improved Sash-Pulley, of which the following is a full, clear, and exact description.

My invention relates to overhead sash pulleys.

An object thereof is to provide pulleys which can be secured to a window frame without any screws.

A further object of the invention is to provide a sash pulley which can be easily and quickly placed into position or removed when necessary.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a fragmentary section through the upper part of the window casing, showing the sash pulley in elevation, a portion of the pulley carrier being broken away to show the details of construction; Fig. 2 is a longitudinal section through the window casing, the sash pulley being shown in elevation and in a position when taken out or placed into the window casing; and Fig. 3 is a longitudinal section on line 3—3, Fig. 1.

Referring to the drawings, the sash pulley consists of a pulley housing 5 and a pulley 6. The pulley housing 5 is provided with a flange 7 at the front wherethrough a portion of the pulley 6 projects slightly, so that the rope going over the pulley will not bear against the flange. The housing 5 has a downwardly projecting lip 9 at the lower edge spaced from the flange. The face of the lip opposite the flange 7 is beveled so that the distance between the flange and the lip decreases toward the housing.

The pulley stile 8 is provided with a mortise 10 for admitting the housing 5 freely

therethrough. The lower edge of the mortise at the rear is beveled, as shown at 11, to fit the beveled side of the lip. The face of the pulley stile 8 has a recess 12 for the flange 7 which extends into the mortise of the head 13 retaining the stile 8. The bottom of the recess 12 within the mortise of the head is depressed to facilitate the insertion of the flange 7 when the pulley housing 5 is placed into the stile 8.

The recess 12 at the lower end is extended far enough to seat the housing 5 on the lower edge of the mortise 10. The flange 7 above the housing does not project out of the mortise when the housing sits on the lower edge of the mortise 10, as shown in Fig. 3. The engagement of the lip 9 with the beveled edge 11 of the stile draws the flange 7 against the stile, the weight carried by the pulley 6 helping the lip 9 to draw the flange 7 into the recess 12 and preventing any accidental displacement of the sash pulley from the stile 8.

It will be noted that the lip 9 clutches the housing in the stile, and to disengage it it is necessary to move the housing 5 bodily upward to bring the lip 9 above the lower edge of the mortise 10 before the sash pulley may be removed. By pulling the lower end of flange 7 out of the recess 12, as shown in Fig. 2, the lip 9 will be out of the mortise; and by pulling downwardly on the sash pulley it may be removed entirely from the sash. The engagement of the flange 7 at the upper end with the head 13 prevents any movement of the housing outwardly in case of a break in the flexible member which carries the weight. That is to say, if by some means the window is caused to move rapidly downward it cannot pull out the sash pulley from the stile 8, for it will be prevented, not only by the lip 9 but also by the engagement of the flange 7 with the head 13.

I claim:

The combination with a window casing having a pulley stile and a head for retaining the stile, of a sash pulley comprising a pulley housing projecting through the stile and having a predetermined vertical displacement in said stile, said housing having a flange projecting into the head of the cas-

ing and adapted to retain its engagement with the head in vertical displacement of the housing in the stile, said housing having a lip spaced from the flange for engaging the 5 stile between said lip and flange when said housing is at its lowermost position within the stile.

In testimony whereof I have signed my name to this specification in the presence of two subscribing witnesses.

WILLIAM A. BRANDT.
